UNITED STATES PATENT OFFICE.

JESSE H. SROFE, OF KOKOMO, INDIANA, ASSIGNOR OF TWO-THIRDS TO
JOHN E. FREDERICK AND HARRY WARD.

DESIGN FOR A WIRE FENCE.

SPECIFICATION forming part of Design No. 31,150, dated July 4, 1899.

Application filed June 9, 1899. Serial No. 719,970. Term of patent 14 years.

To all whom it may concern:

Be it known that I, JESSE H. SROFE, a citizen of the United States, residing at Kokomo, in the county of Howard and State of Indiana, have invented and produced a new and useful Design for Wire Fences, of which the following is a specification.

In the drawing I have shown a side elevation of a wire fence presenting my design.

10 As shown in the drawing, the leading or important feature of my design consists in a fence having horizontal or strand wires A, B, C, D, and E, running longitudinally through the fence, and the double pickets F, having 30 curved tops, which overlap or cross each other above the top of the horizontal or strand wire A and which have inclined portions f, converging toward each other through the space between the strands or wires A and B, 35 and the inclined portions f', diverging from each other through the space between the

strands or wires B and C, and the inclined portions f², converging toward each other through the space between the strands or wires C and D, and the inclined portions f³, 25 diverging from each other through the space between the strands or wires D and E, and so on from the top to the bottom of the fence, and with straight pickets G, running vertically through the fence and bisecting the diamond-shaped spaces formed by the converging and diverging portions of the wire of the pickets.

What I regard as new, and desire to secure by Letters Patent, is—

The design for wire fence herein shown and described.

JESSE H. SROFE.
